DESIGN FOR A HAND MIRROR FRAME

Joseph Casalino, Forest Hills, N. Y., assignor to Dienlast Corporation, New York, N. Y., a corporation of New York

Application October 18, 1944, Serial No. 115,845

Term of patent 3½ years

(Cl. D86—10)

To all whom it may concern:

Be it known that I, Joseph Casalino, a citizen of the United States, residing at Forest Hills Gardens, in the county of Queens and State of New York, have invented a new, original, and ornamental Design For Hand Mirror Frame, of which the following is a specification, reference being had to the accompanying drawing, forming a part thereof.

Figure 1 is a front elevational view of a hand mirror frame showing my new design.

Figure 2 is a side view; and Figures 3 and 4 are
sectional views on the lines III—III and IV—IV, respectively, of Figure 1.

The other side of the frame, not shown, is the same as the side shown in Figure 1.

I claim:

The ornamental design for a hand mirror
frame, as shown and described.

JOSEPH CASALINO.
